(57) **CLAIM**

The ornamental design for a recessed safety anchor, as shown and as described.

DESCRIPTION

FIG. 1 is a front perspective view showing my new design for a recessed safety anchor;
 FIG. 2 is a back view thereof;
 FIG. 3 is a front view thereof;
 FIG. 4 is a right side view thereof;
 FIG. 5 is a left side view thereof;
 FIG. 6 is a top view thereof; and,
 FIG. 7 is a bottom view thereof.

The broken lines included in the Figures above represent part of the article and form no part of the claimed design.

1 Claim, 5 Drawing Sheets(56)
